(57) **CLAIM**

The ornamental design for a device user-control-interface with a detachable display, as shown and described.

DESCRIPTION

FIG. 1 is a front perspective view of a first embodiment of a device user-control interface with a detachable display showing our new design;

FIG. 2 is a right side view of all embodiments thereof;

FIG. 3 is a left side view of all embodiments thereof;

FIG. 4 is a front perspective view thereof, describing a region wherein a keypad may be installed;

FIG. 5 is a front perspective view of a second embodiment thereof;

FIG. 6 is a front perspective view thereof, describing a region wherein a keypad may be installed;

FIG. 7 is a front perspective view a third embodiment thereof, describing regions wherein a keypad and a display may be installed;

FIG. 8 is a front perspective view a fourth embodiment thereof, describing regions wherein a keypad and a display may be installed;

FIG. 9 is a front perspective view a fifth embodiment thereof, describing a region wherein a display may be installed; and, FIG. 10 is a front perspective view a sixth embodiment thereof, describing regions wherein a keypad and a display may be installed.

The broken line showing in the figure drawings is included for illustrative purposes only and forms no part of the claimed design.
